UNITED STATES PATENT OFFICE.

JOHN GIERLASKI, OF CHICAGO, ILLINOIS.

HAIR-CUTTING DEVICE.

Application filed January 11, 1922. Serial No. 528,476.

To all whom it may concern:

Be it known that I, JOHN GIERLASKI, a citizen of the United States, and a resident of Chicago, in the county of Cook and State 5 of Illinois, have invented a new and useful Improvement in Hair-Cutting Devices, of which the following is a full, clear, and exact description.

My invention relates to improvements in 10 hair cutting devices, and it consists in the combinations, constructions, and arrangements herein described and claimed.

An object of my invention is to provide a device of the character described in which 15 the blades may be removed for sharpening when desired.

A further object of my invention is to provide a device of the character described in which the guard may be moved to vary 20 the depth of the cut, that is, to either leave the hair short or long.

A further object of my invention is to provide a device of the character described which is compact in form and which is 25 thoroughly practical for the purpose intended.

Other objects and advantages will appear in the following specification, and the novel features of the invention will be particularly 30 pointed out in the appended claims.

My invention is illustrated in the accompanying drawings, forming part of this application, in which—

Figure 1 is a full perspective view of an 35 embodiment of my invention,

Figure 2 is a rear elevation of a portion of the mechanism shown in Figure 1, and

Figure 3 is a sectional view along the line 3—3 of Figure 2.

40 In carrying out my invention, I make use of a metal handle 1 having a slender neck portion 2 which is bent laterally adjacent its upper end. A metal blade holder 3 comprising a strip of brass or other suitable material, is bent back upon itself so that one side 4 and the opposite side 5, are in substantially parallel relation to one another. At that portion in the holder 3 where the sides 4 and 5 are bent, a tubular member 6 is formed substantially as shown 45 in Figure 3.

The sides 4 and 5 are each bent forwardly at 7 to provide a stop for a cutting blade 8. The tubular member 6 acts as a spring 55 which tends to force the sides 4 and 5 toward one another and thus gripping the

blade 8 tightly therebetween. The blade holder 3 is securely fixed by means of a rivet 9 to the neck 2 of the handle 1.

A guard 10 comprising a plurality of 60 steel bands 11, each substantially U-shaped (see Figure 3), and fixed at one of their ends 12 to a transverse rod 13, serves as a means for holding the blade 8 from direct contact with the scalp. The bands 11 are 65 all in alignment with one another and are spaced equally apart relative to the rod 13. The rod 13 is rotatably mounted on upwardly bent lugs 14 of the side 5 of the blade holder 3. Thus all of guards 11 may move 70 hingedly with respect to the blade holder 3 upon their common center 13.

Means for normally and yieldably holding the guard members 11 so that their outer sides 15 are remote from the edge 16 of 75 the blade 8, is provided in a second transverse rod 17 which is also secured by means of solder or the like to each of the guard members 11. The rod 17 is provided with small rounded knobs 18 at each end thereof 80 and extends out over the edges 19 of the side 5. A pair of torsion springs 20 and 21 are disposed within the tubular member 6 and their adjacent ends secured against movement by a rivet 22. The opposite ends 85 of the springs 20 and 21 extend out of the openings 23 and 24, respectively, of the tubular member 6 and from thence in a straight line to the rod 17 and there terminate in hooks 25 and 26. The hooks 25 and 90 26 serve as a means for engagement of the springs 20 and 21 with the rod 17 and prevent the springs from slipping off of the ends of the rod 17 by their engagement with the knobs 18. The springs 20 and 21 are 95 arranged to press the rod 17 constantly toward the side 5 of the holder 3.

The side 4 adjacent its lower edge 27 is provided with a broad notch 28 which further exposes the blade 8.

100 From the foregoing description of the various parts of the device, the operation thereof may be readily understood. The device is assembled by slipping the blade 8 between the sides 4 and 5 of the holder 3. 105 The device is then applied to the hair with a quick downward stroke. If it is desired to cut the hair close to the scalp, the guard members 11 are pressed closely against the scalp and will thus yield to the pressure and 110 assume the position shown in dotted lines in Figure 3. From the drawing it will be

seen that the distance between the sides 15 of the guard members 11 and the edge 16 of the blade 8 is relatively short. Thus the hair will be cut relatively short. If less pressure is applied, then the guard members 11 will not be moved as far back as shown in the dotted lines and the depth of the cut hair will be governed proportionally.

I claim:

- 10 1. A device of the character described comprising a blade holder adapted to removably support a blade, a handle for supporting said blade holder, and yieldable means for guarding the blade against close engagement with the scalp, said means comprising a plurality of guard members hingedly disposed on said blade holder, and

spring means for normally holding one side of said guard members away from said blade.

2. A device of the character described comprising a blade holder, a blade adapted to be supported in said holder, a handle for supporting said holder, a plurality of spaced apart guard members supported at one end 25 upon a transverse rod, said rod being pivotally mounted on said blade holder, said guard members arranged to pass around the edge of said blade and to normally lie with their ends at a predetermined distance from the opposite side of said blade holder, and a spring for yieldably holding said guard members in said normal position.

JOHN GIERLASKI.
